The appearance of the therapy pack transitions back and forth sequentially between the appearances depicted in the a, b, and c views of each numbered figure set described above and shown. The process or period in which one appearance transitions to another forms no part of the claimed design. Purple is a claimed color in all "a" views described above and shown. Blue is a claimed color in all "b" views described above and shown. White is a claimed color in all "c" views described above and shown. The spheres or beads illustrated in the drawings are drawn so as to appear semi-transparent. The spheres or beads are non-fixed in position relative to one another. The baffle(s) illustrated is/are formed of two transparent pack walls, sealed together to form a thin, flat, planar surface illustrated in the drawings. The shading lines indicate the clear or transparent nature of the therapy pack shell. Structure illustrated in broken lines is environment only and is not otherwise part of the claimed design.
